UNITED STATES PATENT OFFICE.

LEO FEBRE, OF NORFOLK, VIRGINIA.

RIM LOCK.

Application filed September 8, 1924. Serial No. 736,575.

To all whom it may concern:

Be it known that I, LEO FEBRE, a citizen of the United States, residing at Norfolk, in the county of Norfolk and State of Virginia, have invented a new and useful Rim Lock, of which the following is a specification.

This invention aims to provide novel means whereby a demountable rim may be held releasably on a wheel felly, it being possible to mount the rim on the felly and to remove the rim from the felly quickly and with the expenditure of little effort.

It is within the province of the disclosure to improve generally and to enhance the utility of devices of that type to which the invention appertains.

Although a preferred form has been shown in the drawings, it will be understood that a mechanic, working within the scope of what is claimed, may make changes without departing from the spirit of the invention.

In the accompanying drawings:—Figure 1 shows in side elevation, a wheel equipped with the device forming the subject matter of this application, parts being broken away; Figures 2, 3 and 4 are sections, taken respectively, on the lines 2—2, 3—3, and 4—4 of Figure 1; Figure 5 is a cross section showing the lug on the rim interengaged with the shiftable ring on the wheel felly; Figure 6 and Figure 7 are sections on the line 6—6 of Figure 5 and showing the retaining ring in slightly different positions; Figure 8 is a fragmental circumferential section wherein parts appear in elevation.

The wheel felly 1 may be of any desired sort, but, preferably, is trough-shaped, including a base 2, and side flanges 3 and 4, the flange 3 having openings or notches 5 in its outer edge. A bracket 6 is secured to the base 2 of the felly 1, and on the bracket, an angular lever 7 is fulcrumed at 8, one end of the lever extending through an opening 9 in the base 2 of the felly 1, and the other end of the lever extending circumferentially of the felly 1, along the base 2 thereof, as shown in Figures 1 and 8. The lever 7 is adapted to be swung in a plane parallel to the plane of the wheel, and in order to hold the lever 7 against the base 2 of the felly 1, a latch means of any sort is provided. The latch means may be in the form of a screw 10 held for rotation but against longitudinal movement in the free end of the lever 7, the screw being adapted to be threaded

into the base 2 of the felly 1. At its outer end, the lever has a fork 11. At a point remote from the lever 7, a bracket 12 is secured at 14 to the base 2 of the felly 1, the bracket being of U-shape and being provided with openings 15, there being an opening 16 in the bracket, between the openings 15. The numeral 17 marks a circumferentially movable member, preferably in the form of a ring, held for rotation on the base 2 of the felly 1 between the flange 3 of the felly, on the one hand, and the inner end of the lever 7 (Figure 2) and the bracket 12 (Figure 3) on the other hand. The ring 17 is supplied with circumferentially spaced feet 18, which bear immediately upon the base 2 of the felly 1, the major portion of the ring being spaced, by the feet 18, from the base 2 of the felly 1, as disclosed in Figure 8, so that the circumferential movement of the ring will not be interfered with by dirt which may find its way into the felly 1. The ring 17 has a lateral projection 19 received in the fork 11 of the lever 7. In the outer edge 80 of the ring 17 there are notches or openings 20, adapted to be brought into registration (Figure 6) with the notches or openings 5 in the flange 3 of the felly 1, when the ring 17 is shifted circumferentially. The ring 17 is 85 beveled as at 21, on its inner surface, and at one end of each opening 20.

The rim 22 may be of any desired construction, the tire on the rim being designated by the numeral 23, and the inflating valve stem being designated by the numeral 24. The base of the rim 22 carries lugs 25.

In practical operation, the latch screw 10 is released from the base 2 of the felly 1 and the lever 7 is swung from the solid line position of Figure 8 to the dotted line position of that figure, circumferential movement being imparted to the ring 17, because the projection 19 of the ring is engaged with the fork 11 of the lever 9, the notches 20 of the ring 17 being brought into registration with the notches 5 in the side flange 3 of the felly 1, as shown in Figures 4 and 6. Then, the rim 22 may be 105 slid transversely into place, in the direction of the arrows in Figures 4 and 6, the lugs 25 passing through the aligned notches 20 and 5, the lugs ultimately abutting against the side flange 4 of the felly 1, as shown in Figures 5, 6, and 7. The lever 7 is swung back to the position shown in solid lines 110

in Figure 8, and the latch 10 is engaged with the base 2 of the felly 1, circumferential movement being imparted to the ring 17, the notches 20 in the ring being moved 5 out of registration with the notches 5 of the felly, the ring 17 bridging the notches 5 of the felly, as in Figure 7, and cooperating with the lugs 25 to hold the rim 22 in place. Because the ring 17 is beveled as at 10 21, and because the lugs 25 are correspondingly beveled, as at 26, the rim 22 will be moved laterally when the ring 17 is shifted circumferentially, and the lugs 25 on the rim will be carried over into abutment with the 15 flange 4 of the felly 1, as in Figures 5 and 7.

In mounting the rim 22 on the felly 1, the inflating valve stem 24 is introduced into the opening 16 of the bracket 12, and 20 into a corresponding opening 27 in the base 2 of the felly 1, projections 28 on the rim 22 being received in the openings 15 of bracket 12, the rim then being moved transversely, in the direction of the arrows in 25 Figures 4 and 6, until the rim occupies the position depicted in Figure 5.

In order that the ring 17 may be mounted on the felly 1, the ring may consist of

two or more parts having their ends 30 overlapped and beveled, the ends 30 of the parts 30 of the ring being held together by securing elements 31.

What is claimed is:—

In a device of the class described, a felly comprising a base and side flanges, a ring 35 rotatable on the base, the ring and one flange having openings adapted to be brought into registration when the ring is rotated, a rim having lugs adapted to enter the openings when they are in registration and when 40 the rim is moved transversely of the felly, mechanism carried by the felly for rotating the ring, a single bracket mounted on the base of the felly and located about opposite to said mechanism, the bracket and said 45 mechanism forming the sole projections on the outer surface of the base of the felly, and means for connecting the bracket with the base of the felly, the ring being held for rotation between said flange on the one 50 hand, and said mechanism and the bracket on the other hand.

In testimony that I claim the foregoing as my own, I have hereto affixed my signature.

LEO FEBRE.
